UNITED STATES PATENT OFFICE.

ARISTIDE L. N. CREMO AND ALBERT J. GORDON, OF ATTLEBORO, MASSACHUSETTS, AS-SIGNORS OF ONE-THIRD TO JOSEPH E. GAYNOR, OF ATTLEBORO, MASSACHUSETTS.

ELECTRIC TIME SWITCH FOR AUTOMOBILE LIGHTS.

Application filed April 6, 1925. Serial No. 21,094.

The present invention appertains to an electric time switch for automobile lights, and has for its principal object to provide means which can be set, and depended upon 5 to display a light at the predetermined time, said means being automatically operable when set or adapted to be manually actuated at any time to admit of the light being displayed. This invention is of importance 10 since, at the present time, in the operation of motor vehicles it frequently happens that the same are left unattended for a period extending past nightfall, thereby subjecting the owner or operator to a penalty for failure 15 to display a light which is universally required by traffic regulations, and furthermore an operator of a motor vehicle often forgets to display his lights as nightfall approaches.

Another important object of the invention 20 is to provide an electric time switch of this nature, which is easily adjustable so that the lights will be displayed at the desired time, and one which is exceedingly simple in its 25 construction, easy to install as part of the light circuit of an automobile, efficient and reliable in its operation, not liable to easily become out of order, and otherwise well 30 adapted to the purpose for which it is designed.

Another specific object of the invention is to provide a circuit closing key which will be efficient in preventing theft of the automobile.

With the above and numerous other objects in view as will appear as the description proceeds, the invention resides in certain novel features of construction, and in the combination and arrangement of parts 40 as will be hereinafter more fully described and claimed.

In the drawing:—

Figure 1 is a front elevation of the device embodying the features of my invention.

Figure 2 is a fragmentary section taken therethrough.

Figure 3 is another fragmentary section taken therethrough.

Figure 4 is a diagrammatic view showing 50 the wiring incident to the invention.

Referring to the drawing in detail, it will be seen that 5 designates a casing mounted on a plate 6 so that it may be attached to

the dash board of an automobile, or in some other suitable and convenient position. 55 The front wall or panel 7 of the casing 5 provided with an arcuate slot 8 having hours, and fraction of an hour indicated thereon by suitable indicia 9. A shaft 10 is rotated by the hour hand shaft of a clock 60 mechanism of any suitable nature. On this shaft 10 there is mounted a gear 11 which meshes with a gear 12 rotatable on the shaft 13. A hub 14 is rotatable on the shaft 13, and a spring 15 is disposed about the hub 65 for impinging against the collar 16 thereof and a nut 17 so that the collar 16 will be held in frictional engagement with the gear 12 and be normally rotated thereby. An indicator 18 projects from the collar 16 and is bent to extend through the slot 8 and terminates in a pointer 19 for cooperating with the indicia 9. An insulating washer 20 is disposed between the collar 16 and gear 12. A wire 21 is connected to the indicator 18 75 and a wire 22 is connected to the contact terminals 23. If, by way of example, the lights 24 should be turned on within four and one half hours, the hand or indicator 18 would be set at four and one half on the 80 indicia 9, and thus it will be seen that after this amount of time transpires, the point 19 of the indicator will contact with the terminal 23, thereby closing a circuit as will be evident from an inspection of Figure 4. 85 The clock mechanism will continue to rotate, and the gear 12 will also continue to rotate, but it will merely slip in relation to the indicator, and have no further effect thereon. It will be seen that the indicator may 90 at any time be manually moved so as to engage the fixed contacts 23.

A slot 25 is provided in the panel 7. An insulator base 26 is mounted in the casing 5 with two arcuate spring fingers 27 thereon 95 which are connected with a wire in the ignition circuit of the automobile as is indicated to advantage in Figure 4. A key 28 has a curved terminal 29 for engagement with one spring finger 27 and a curved spring finger 30 for cooperating with the other spring finger and thereby may be inserted through the slot 25 for closing the ignition circuit. The handle 31 is made of insulating material so that the operator will not obtain a 100 105 shock. Thus when the operator is about to

5 leave the car he may pull out this key 28 and it will not be possible for unauthorized persons to start the car. This key, of course, is supplemental to the ordinary ignition lock key.

10 It is thought that the construction, operation, and advantages of this invention will now be clearly understood without a more detailed description thereof.

15 The invention provides a comparatively simple mechanism which is positive in operation, and which may be set and depended upon to operate at the predetermined time so that a motor vehicle may be left unattended, and that at the required time will be provided with the lights without any special care on the part of the owner or operator, other than to properly set the circuit closer when the machine is left unattended.

20 It will further be apparent that the present embodiment of the invention has been given merely by way of example in order to disclose means whereby the advantages of the invention may be attained. It is to be un-

25 derstood, that numerous changes in the details of construction, in the materials, in the sizes and the proportions, and in the combination and arrangement of parts may be resorted to without departing from the spirit

or scope of the invention as hereinafter claimed or sacrificing any of its advantages.

Having thus described the invention, what we claim as new is:—

25 In a device of the class described, a casing, a front panel for the casing, said front panel being provided with an arcuate slot having one end slightly offset, a fixed contact at said offset end, of the slot, a shaft mounted for rotation in the casing, a gear rotatable on the shaft, an insulating washer 40 on the shaft next to the gear, an indicator having a hub portion rotatable on the shaft, a spring associated with the hub portion holding it in frictional engagement with the washer and the washer in frictional engagement with the gear, a time controlled mechanism gear meshing with the first mentioned gear, said indicator being bent intermediate 45 its ends so that its free extremity is offset, the intermediate bent portion extending 50 through the slot, so that when the indicator is actuated to said end of the slot, it will engage the fixed contact for closing a circuit.

55 In testimony whereof we affix our signatures.

ARISTIDE L. N. CREMO.
ALBERT J. GORDON.
